FUEL SUPPLY TANK

Mogens Louis Bramson, Elstree, England

Application February 18, 1942, Serial No. 431,415
In Great Britain October 23, 1940

23 Claims. (CL 222—63)

This invention relates to liquid supply tanks, and is especially applicable to liquid fuel supply tanks in military aircraft.

It is an object of the present invention to provide a tank from which the possibility of leakage and loss of large quantities of fuel due to damage by projectiles is largely avoided.

The invention consists in a liquid supply tank comprising a container enclosing a plurality of inner compartments each with its own outlet separate from the outlet from the container, non-return valves being provided to prevent reverse flow into each inner compartment.

In order that it may be clearly understood and more readily carried into effect, the invention is hereinafter described with reference to the accompanying diagrammatic drawings, of which:

Figure 1 is an elevation (mainly in section) of a typical fuel tank according to the present invention arranged for installation in an aircraft wing;

Figure 2 is a plan view looking down on the top of the fuel tank as shown in Figure 1, the top of the tank and a part of the internal assembly of tubular compartments being broken away to reveal the interior fittings;

Figure 3 is a fragmentary perspective view illustrating the method of suspending the individual compartments of the honeycomb of inner compartments from the top of the tank;

Figure 4 is an enlarged fragmentary detail of a collector box sectioned to show the construction of one of the non-return valves provided in the outlets from the individual compartments of a honeycomb of inner compartments provided within the fuel tank;

Figure 5 is a very diagrammatic view illustrating a typical fuel supply system embodying a fuel tank according to the invention;

Figure 6 is a side elevation in section of a combined junction box and jettison valve embodied in the system according to the present invention;

Figure 7 is a plan view corresponding to Figure 6, partly broken away; and

Figure 8 is an elevation partly in section showing an electrically-driven fuel pump which operates to ensure preferential feed from the outer compartment of the container at all times when liquid is available there.

Referring first to Figures 1, 2 and 3 of the accompanying diagrammatic drawings, the fuel tank 9 is hollow and is closed by the top cover plate 10, which may form a detachable panel of the wing structure. A honeycomb structure

constituted by a plurality of inner compartments 11 within the tank 9 is suspended from the cover plate 10. The inner compartments 11 are provided laterally with upstanding lug portions 12 which are eyeleted, as indicated particularly clearly at 13 in Figure 3. Wires 14 pass through the eyelets 13, and thus each wire 14 suspends a row of the individual compartments 11. The wires 14 in their turn are supported on the intersecting wires 15, which are carried by the angle sections 16 secured to the top cover plate 10 in any convenient manner, as for example by riveting. It will be noted from Figure 3 that the intersecting wire 15 illustrated therein is turned over at its end, as indicated at 15a, which arrangement provides a convenient manner of locating the wire 15 against endwise displacement, and the ends of the wires 14 are located by the girders 17 (see Figure 2) in the same way as the wires 14 are located by the girders 16; which support means however do not appear in the drawings.

It is apparent that each honeycomb cell or individual compartment 11 is open at the top and is thus capable of being filled with liquid fuel. At the bottom of each compartment 11 there is provided for each compartment an outlet pipe connection 18, which leads to the interior of a collector box 19 by engagement with the plate 20 (see Figure 4). Each outlet pipe connection 18 has at its outer or lower end within the collector box 19 a non-return valve, the purpose of which will become apparent from the ensuing description. The collector boxes 19 are fed from grouped pipe connections 18, and from each collector box a fuel supply conduit 22 runs to the junction box 23.

It will be noted that the honeycomb structure of individual compartments 11 is spaced from the tank walls and from the bottom of the container. When liquid fuel is introduced into the tank 9 through the filler orifice 24 the liquid fuel fills up the honeycomb of individual compartments 11. A baffle plate 25 is provided all round the periphery of the tank to prevent the passage of liquid fuel into the outer compartment constituted by the space in the tank 9 surrounding the honeycomb structure.

Indicated by the reference numeral 26 in Figures 1 and 3 is a netting of wire mesh, the meshes of which fit the individual compartments 11, and the meshes themselves being located to lie at spaced intervals, each fitting as a framework within the tank 9. The purpose of the mesh is

to prevent excessive swaying of the assembly of inner compartments 11.

There are two features which occur in Figure 2 resulting from the fact that the tank illustrated is one which has been adapted to replace an existing tank in an aircraft wing. The first of those features consists in the displacement of the outlet flow pipe from the junction box 23. The outlet flow pipe 27, inside the tank, runs from the junction box and out through a sump, indicated in dotted lines at 28. The pipe 21 merely extends to a pipe fitting in the sump, and from the sump runs the external pipe 27'. Such an adaptation makes it possible to instal the tank without making any alteration to the existing main fuel supply piping. The sump 28 is open to the interior of the tank, as is also the pipe 29 through which any liquid collecting in the tank 9 below the assembly of inner compartments 11 and above the sump can flow away, as will later be described.

The second feature which has been introduced in the tank shown is the inclusion of the pillar 30. In actual fact, there will generally be more than one pillar provided but only one is shown in the drawings. The necessity for the pillar 30 arises from the fact that in the machine for which the tank has been adapted the wing is stressed to take the weight of the tank on a bottom platform. In a tank according to the present invention the whole of the interior mechanism is suspended from the top of the tank and a pillar 30 merely serves to transmit the load therefrom to the bottom of the tank. Where a pillar or pillars 30 is or are provided, it is convenient to utilise them to assist in locating the netting 26, which may engage the pillar as well as all of the inner compartments 11, and which may at its periphery engage the locating channels 32 at the outer wall of the tank.

Referring now to Figure 4, each outlet pipe 18 is provided at its end remote from its associated inner compartment 11 with a nipple 33 which leads through the top plate 20 of the collector box 19, and internally of the collector box the nipple 33 is engaged by the cage 35 within which there is a buoyant float 36. The cage 35 has radial ports 37 disposed at or about the level of the outlet from the nipple 33 into the connector box, and the end wall of the cage 35 is ported, as indicated at 38. The arrangement is such that so long as there is any flow from the outlet pipe 18 the float 36 is pressed down towards the lip 39 of the cage 35 and liquid thus flows out of the ports 37, as indicated by the arrows, into the collector box, from the interior of which the pipe 22 leads away to the junction box. If the flow from any one compartment 11 should cease in the event of a compartment 11 or pipe 18 becoming damaged, for example by a projectile, and discharging the liquid into the tank 9, the float 36 being buoyant in the liquid in the collector box and being no longer urged downwardly by the flow from the associated pipe 18, lifts to close off the seat 40 at the end of the nipple and thereby prevents reverse flow, such as might permit liquid to flow back into the damaged compartment and continue to leak out into the tank 9.

Figure 5 illustrates in a very diagrammatic form a fuel supply system according to the present invention embodying two tanks 9. Under all normal circumstances there is no liquid in the part of the tank below or surrounding the assembly of inner compartments 11, described with reference to Figures 1 and 3, and fuel therefore is drawn along the pipe 27' by the fuel pump 41 and dis-

charged to the engine along the main fuel supply conduit 42. If at any time liquid collects in the tank 9 below the assembly of inner compartments 11, the fuel collected in the tank 9 then flows along the conduit 29 to the float chamber 43 of an electric fuel pump 44. The fuel pump 44 includes the float-actuated switch 45 and is driven by the battery, indicated at 46. The arrangement is such that when the float is raised under the influence of fluid delivered to the float chamber from the part of the tank 9 below the assembly of inner compartments 11, the switch is actuated to drive the pump, which then discharges along the conduit 47 and through the non-return valve 70 to the main engine supply pipe 42. The pump 44 is chosen to be capable of delivering a pressure slightly greater than the delivery pressure of the main fuel pump 41, and there is provided between the conduit 47 and the main fuel pump 41 a non-return valve 48 which is closed when fuel is being delivered along the conduit 47 from the pump 44. The arrangement thus ensures preferential feeding of fuel from that part of the tank 9 below the assembly of inner compartments 11 at all times when liquid finds its way into the tank below the inner compartments.

It will now be realised that if any of the inner compartments 11 become damaged, for instance by a projectile, all that happens is that each damaged compartment discharges liquid down to the level of the fracture, and the discharged liquid is collected in the tank 9 below the compartments 11. Provided the projectile does not pass through the tank 9 at a point at or fairly near the bottom, the petrol discharged from the damaged compartment or compartments will merely collect in the part of the tank 9 below the compartments and will preferentially be used up. As external leakage is likely to occur only if the tank 9 is penetrated at or near the bottom, there is in the case of fuel tanks provided over the bottom and for a few inches up the side wall a covering layer of fuel leak-sealing materials 49 (see Figures 1, 2, 4 and 5) of one of the already well known types.

To recapitulate, normal flow is from a group of individual cells 11 via each outflow tube 18 and past each individual float valve 36 to their common collector box 19; from the group of collector boxes 19 via each individual outflow tube 22 to the common junction box 23; and thence to the normal fuel pump 41 via pipe 27, sump 28 and pipe 21. While all this flow, to the junction with the sump, is within the tank 9, the flow passages described are independent of the tank and of the latter's drain conduit 29, and the tank may be considered only as a receiver to collect overflow in the event of rupture of any such cell or flow passage.

Should rupture of any cell 11 or tube 18 occur, only the fuel above the rupture in this particular cell or tube will leak into the portion of the tank surrounding the cells. When this cell has emptied, either through the rupture, or its tube 18 into collector box 19, or both, the corresponding float valve 36 will act to prevent equalization of liquid level—and consequent leakage from liquid-containing cells into the damaged cell or tube to pass through the rupture into the cell-encircling space. The undamaged cells will continue normal flow, and only the damaged cells or tubes, of small capacity relative to the whole, will be sealed off. As the general liquid level in the cells is lowered to that of each damaged cell, determined by its lowest leak, it will again contribute its normal flow to that from the undamaged cells.

However, in order promptly to empty the space in the tank exteriorly of the cells of liquid escaped from damaged cells, the float-controlled pump 44 comes automatically into operation. Before further withdrawal from the cells 11 can occur, all leakage collected within the tank 9 is withdrawn, and only then does the pump 44 resume withdrawal from the cells 11.

Should one of the tubes 22 or one of the collector boxes 19 be ruptured, all cells feeding thereto will drain into the interior of the tank through the rupture, but still the other cells will be sealed off by the valves 52, shortly to be described, until such time as the leakage collected in the tank has been drained off via pump 44.

Referring now to Figures 6 and 7 which illustrate the junction box, it should be realised that the junction box in this case also includes a jettison valve. The device shown in Figure 6 is that referred to by the reference numeral 23 in Figure 1, and comprises a body casting within which segmental spaces 50 are fed with fuel through the conduits 22 running from the various collector boxes 19. Fuel running to the junction box along the conduits 22 passes up through the valve ports 51, causing the valves 52 to be lifted from their seatings, thereby allowing the fuel to flow into the chamber 53. In order to locate the valves 52, the pins 54 are provided. Fuel from the chamber 53 flows away from the junction box through the conduit 27 (see also Figure 1). The valves 52 close automatically to prevent reverse flow from any one or more of the associated groups of inner compartments 11 to another or others which have become empty, for instance through damage to a conduit 22 of a collector box 19.

Leading from the chamber 53 is a jettison valve opening 55 which is of substantial area to provide for quick jettisoning of fuel in emergency. In the ordinary course of events the jettison valve opening 55 is closed by the valve 56 which is normally seated over the inner end of the opening 55, being spring-loaded for closure by means of a compression spring 57. Located in a boss 58 centrally below the valve 56 is a valve-actuating rod 59 having a roller 60 at its lower end. The roller 60 engages an edge cam 61 mounted on the inner end of a jettison valve-actuating lever 62. The lever 62 is pivoted to the body of the combined jettison valve and junction box to swing about the axis 63 and is actuated by the operating rod 64 from the cabin of the aircraft. Pulling the operating rod 64 in the direction of the arrow shown in Figure 7 swings the jettison valve-actuating lever 62 anticlockwise, with the result that the valve-actuating rod 59 is lifted to open the jettison valve 56.

Figure 8 is merely an additional detail view illustrating one convenient arrangement of float-controlled pump operable to ensure preferential delivery of fuel from that part of the tank 9 below the assembly of inner compartments 11 at all times when fuel is discharged into that outer part of the tank. The float-controlled pump is seen in Figure 5 of the drawings, and those reference numerals which remain applicable to the particular description at this stage of the specification are retained. Thus, 43 indicates a float chamber, 44 the electrically-driven pump per se, 45 the float-controlled switch, and 47 the outlet conduit leading off to the engine; and those references can also be seen in Figure 5. Within the float chamber is the float 65 which rises under the influence of liquid entering the float chamber through the conduit 29 from the bottom of the

tank 9. The float engages a toggle-link system 66 including balance weights 67, and the arrangement is such that raising of the float 65, which occurs under the influence of liquid entering the float chamber 43, causes the toggle-links to swing about their pivots 68 to operate the switch-actuating plunger 69, a small movement of which results in completion of the circuit from the battery 46 of Figure 5 to the motor for driving the latter.

Instead of forming the honeycomb compartments 11 each as a self-contained tube complete in itself, the assembly of inner compartments 11 can be built up from sheet material as a complete honeycomb by cementing together sheet upon sheet, the adhesive between adjacent sheets being appropriately localised in stripes running across the sheets. If hexagonal compartments are required with, for example, one-inch sides, stripes of adhesive one-inch wide and three inches apart will be used between successive sheets, but staggered so that the stripes cementing one pair of contact surfaces will be located midway between the stripes cementing the next succeeding pair of contact surfaces. It then follows that if the layers so cemented are pulled apart to the requisite extent as permitted by the uncemented portions of the various contact surfaces, a continuous honeycomb with hexagonal compartments is obtained.

The individual compartments 11 of the honeycomb may be of any desired material, such for example as fabric coated with synthetic rubber or synthetic resinous material.

What I claim is:

1. A liquid supply system comprising a container, a plurality of compartments enclosed within said container to leave a chamber therein encompassing said compartments to catch liquid from any of said compartments which may become ruptured, a receiver, an outlet leading from each compartment to said receiver, and non-return valve means controlling flow through each compartment outlet, movable to open position by pressure of liquid in such outlet and its compartment for flow of liquid simultaneously from all said compartments to said receiver through their several outlets, but operable automatically to prevent reverse flow from said receiver, through the outlet of any one of said compartments which may become ruptured, and through such compartment into such encompassing chamber.

2. A tank comprising a container, a honeycomb structure of open-topped internal compartments suspended from the top of the container, and each having its own fuel feed outlet separate from a fuel feed outlet from the container, the honeycomb structure being spaced from the interior of the container, and flow-resisting baffle means extending between the honeycomb structure and the top of the container whereby to ensure that liquid poured into the container through a filler opening in the top thereof will flow preferentially into the honeycomb, whereby the space within the container surrounding the honeycomb structure either will remain empty, or will be filled substantially only when the honeycomb overflows.

3. A liquid supply system comprising a tank having within it a plurality of compartments each open at its top but closed at its bottom, the bottoms of such compartments being spaced above the tank's bottom to form in the tank beneath the compartments a collection chamber, two outflow pipes leading from the bottom of the tank, one

whereof is open to said chamber, a plurality of outlet tubes, one from each compartment, communicating with the other outflow pipe, for normal flow, non-return valve means interposed between the latter outflow pipe and each compartment to prevent reverse flow back through each outlet tube, means normally operative to draw off fluid through said tubes and past said non-return valve means, and thence through the second outflow pipe, and means responsive to presence of liquid within said chamber or first outflow pipe to induce draw-off from said chamber through said first outflow pipe in preference to outflow through said second outflow pipe.

4. A liquid supply system comprising a tank having within it a plurality of compartments each open at its top but closed at its bottom, the bottoms of such compartments being spaced above the tank's bottom to form in the tank beneath the compartments a collection chamber, two outflow pipes leading from the bottom of the tank, one whereof is open to said chamber, a plurality of outlet tubes, one from each compartment, communicating with the other outflow pipe, for normal flow, non-return valve means interposed between the latter outflow pipe and each compartment to prevent reverse flow back through each outlet tube, means normally operative to draw off fluid through said tubes and past said non-return valve means, and thence through the second outflow pipe, means responsive to presence of liquid within said chamber or first outflow pipe to induce draw-off from said chamber through said first outflow pipe in preference to outflow through said second outflow pipe, a normally-closed jettison valve disposed at the entrance to the second outflow pipe, and means operable at will to open said jettison valve, to drain all said compartments.

5. A tank as defined in claim 1, wherein the compartments are tubular in form, and means suspending the compartments substantially vertically within the container.

6. A tank as defined in claim 1, wherein the compartments are tubular in form, extending substantially vertically, the bottom of each compartment being closed, and spaced above the bottom of the container.

7. A tank as defined in claim 1, wherein the compartments are tubular in form, extending substantially vertically, the bottom of each compartment being closed, and spaced above the bottom of the container, and a leak-sealing material coating the bottom of the container and the lower portion of each side of the container up to a level at least as high as the bottoms of the compartments operable to retain within the lower portion of the container liquid leaked from a ruptured compartment.

8. A tank as defined in claim 1, including a removable top, the compartment-forming means being suspended from said top.

9. A tank as defined in claim 1, wherein the compartments are each complete, and disposed contiguously to other such compartments to occupy the major portion of the space within the container.

10. A tank as defined in claim 1, wherein the compartment-forming means consists primarily of flexible material.

11. A tank as defined in claim 1 including a plurality of receivers, the compartments being grouped into a like number of groups, and the outlet tubes of each group leading to its appropriate receiver, common to all compartments of

the group, and discharge means leading from each receiver.

12. A tank as defined in claim 1 including a plurality of receivers, the compartments being grouped into a like number of groups, and the outlet tubes of each group leading to its appropriate receiver, common to all compartments of the group, and discharge means leading from each receiver, a junction box to which the several discharge means lead, and an outflow pipe leading from said junction box.

13. A tank as defined in claim 1 including a plurality of receivers, the compartments being grouped into a like number of groups, and the outlet tubes of each group leading to its appropriate receiver, common to all compartments of the group, and discharge means leading from each receiver, a junction box to which the several discharge means lead, an outflow pipe leading from said junction box, and additional non-return valve means governing each such discharge means, at the junction box, to prevent reverse flow through said discharge means to the receivers.

14. A liquid supply tank comprising an outer container, a plurality of independent cells within said container, means to drain each cell, including a valve within the container and associated with each cell, arranged to open by outflow from its cell and to close by flotation upon liquid collected within the container, to regulate flow of liquid from each cell for maintaining the level of liquid in all said cells at the same height, and draw-off means connected to all the individual cells past their individual valves.

15. A liquid supply tank comprising an outer container, a plurality of independent cells contained therein, drain means connected to each cell, a receiver to which all said drain means are connected in common, a drain leading from the receiver, a separate means to drain the container, non-return valve means operable under the influence of liquid collected within the receiver to prevent reverse flow into the cells, and means automatically operable under the influence of liquid collected within the container to effect drainage therefrom in preference to withdrawal from the receiver and thence from the individual cells.

16. A liquid supply system comprising a cluster of separate compartments, a receiver, a plurality of outlets, each connecting the lower end of a different compartment with a chamber in the receiver common to all said outlets, and an individual non-return valve controlling flow through each outlet, movable to open position by gravity pressure of liquid in such outlet and its compartment for flow of liquid therefrom to said receiver, and closable by superior hydrostatic pressure of liquid in said receiver to regulate flow of liquid from each compartment outlet for maintaining the level of liquid in all said compartments at the same height.

17. A liquid supply tank comprising a container, means therein subdividing its interior space into a plurality of compartments all open at the top to the interior of the container, a receiver common to all said compartments, each compartment having an individual outlet leading from its bottom to said common receiver, and buoyant non-return valve means governing each outlet, movable to open position by pressure of liquid in such outlet and its compartment, and closable by the buoying action of liquid in said common receiver upon cessation of such flow to

prevent reverse flow into the bottom of such compartment from said common receiver.

18. A liquid supply tank comprising a container, honeycomb partitions therein subdividing its interior space into a plurality of compartments, all open only at the top to the interior of the container, and a common collection chamber for receiving liquid leaking from such compartments, an outlet sump in the bottom of the common collection chamber, a plurality of tubes leading from said compartments and communicating with said sump, for flow of liquid from the compartments to the sump, an outlet from said sump, and non-return valve means controlling flow of liquid through said tubes to prevent reverse flow through any of said tubes into the common collection chamber from any other of said tubes.

19. A liquid supply tank comprising an outer container, a plurality of independent cells contained therein, said container defining a common collection chamber for receiving liquid leading from such compartments, drain means connected to each cell, a receiver to which all said drain means are connected in common, a drain leading from the receiver, a separate drain leading from the common collection chamber of the container, and non-return valve means operable automatically during removal through said separate drain of liquid leaked into the common collection chamber to prevent flow of liquid from the cells through said first drain.

20. An airplane fuel supply system or the like, comprising a tank having within it a plurality of compartments each open at its top but closed at its bottom, and elevated above the tank's bottom to define beneath them a collection chamber, two outflow pipes leading from the bottom of the tank, one whereof is open to said chamber, a sump whence the second leads, a plurality of tubes leading from said compartments and communicating with the sump, for normal flow of liquid from the compartments to the sump, non-return valve means controlling flow of liquid through said tubes to prevent reverse flow therethrough back from the sump to the compartments, means normally operative to draw off fuel through the tubes and sump, past the non-return valve means, and thence through the connected outflow pipe, and alternative means responsive to presence of fuel within said collection chamber or the outflow pipe open therefrom, to withdraw liquid from such chamber through its outflow in pipe in preference to outflow from said sump through its outflow pipe.

21. An airplane fuel supply tank or the like, comprising a container having within it a plurality of compartments each open at its top but closed at its bottom, a sump located at a level below the bottoms of the compartments, an outflow pipe leading from the sump, a plurality of receivers, a plurality of outlet tubes, each connected to one of said receivers and leading from a different compartment, a plurality of receiver tubes each connected to a different receiver and communicating with the sump, for normal flow of liquid from said compartments to the sump, a non-return valve controlling flow through each outlet tube operable to prevent reverse flow of liquid back to its compartment from the receiver to which it is connected, and a non-return valve controlling flow through each receiver tube operable to prevent reverse flow of liquid back to its receiver from the sump.
- 20 22. An airplane fuel supply tank or the like, comprising a container having within it a plurality of compartments each open at its top but closed at its bottom, a junction chamber located at a level below the bottoms of the compartments, an outflow pipe leading from the junction chamber, a plurality of tubes connected to said junction chamber and leading from said compartments for normal flow of liquid therefrom to the junction chamber, a non-return valve controlling flow of liquid through each tube to prevent reverse flow therethrough back from the junction chamber to the compartments, a normally-closed jettison valve associated with the junction chamber, interposed between the non-return valves and the outflow pipe, and means operable at will to open said jettison valve, to drain all said compartments.
- 40 23. A tank for containing liquid, comprising a container, a multitude of compartments housed within said container and spaced above the bottom thereof to leave a normally empty collection chamber therebelow within the container, for receiving leakage from said compartments, common outlet means interconnecting said compartments, a drain leading from the normally empty collection chamber of said container separate from said common outlet means, and means automatically operable under the influence of liquid collected in such collection chamber to effect drainage therefrom in preference to withdrawal of liquid from said common outlet means and thence from the individual compartments.

MOGENS LOUIS BRAMSON.
